UNITED STATES PATENT OFFICE.

JOSEPH H. POTTER, JR., OF FALL RIVER, MASSACHUSETTS, ASSIGNOR OF ONE-HALF TO EZRA DIXON, OF BRISTOL, RHODE ISLAND.

SPINNING-MACHINE.

SPECIFICATION forming part of Letters Patent No. 436,317, dated September 9, 1890.

Application filed March 18, 1890. Serial No. 344,376. (No model.)

To all whom it may concern:

Be it known that I, JOSEPH H. POTTER, Jr., of Fall River, in the county of Bristol and State of Massachusetts, have invented a new and useful Improvement in Spinning-Machines; and I hereby declare that the following is a full, clear, and exact description of the same, reference being had to the accompanying drawings, forming part of this specification.

This invention has reference to an improvement in the mechanism for reciprocating the roving-rod and guide-eyes, or trumpets, by which the roving is delivered and guided onto the drawing-rolls in spinning-machines; and it consists in the peculiar and novel construction of a weighted lever operated by a heart-shaped cam driven and supported as will be more fully set forth hereinafter.

In spinning-machines the roving is delivered between the drawing-rolls and top rolls through guide-eyes or trumpets supported on a rod called the "roving-rod." As the top rolls are liable to wear into grooves if the roving is delivered for a considerable time at the same point, it becomes necessary to change the point at which the roving enters slowly but constantly, and thereby wear the top rolls evenly. To this end it is important to give to the roving-rod a slow reciprocating motion, so as to change continually the point of wear on both the top and the drawing rolls. In any mechanism for accomplishing this reciprocation the slightest backlash at the ends of the reciprocations will wear grooves near the ends of the top rolls, and in time even into the drawing-rolls, not only injuring these parts unnecessarily, but making them useless for successful and practical spinning.

To obviate these difficulties, secure absolutely uniform reciprocation, and uniform wear in these parts, is the object of this invention; and this I accomplish by reciprocating the roving-rod by means of a bell-crank lever, one arm of which is connected with the roving-rod, one arm is provided with a weight, and the third arm operated by a heart-shaped cam.

Figure 1 is an end view, partly in section, of the drawing-rolls of a spinning-machine,

showing the device for reciprocating the roving-rod. Fig. 2 is a view of the roving-rod, the operating bell-crank lever, the weight, and the cam, showing the worm and worm-gear for rotating the cam. Fig. 3 is a view of the adjustable bracket in which the operating bell-crank lever and the cam are supported. Fig. 4 is a plan view of the device showing the cam and worm-gear in section.

Similar numbers of reference indicate corresponding parts in the drawings.

The number 5 indicates the rail or part of the frame of a spinning-machine on which are secured the stands in which the drawing-rolls are supported.

6 indicates the standard; 7, the drawing-rolls; 8, the front or delivery roll, and 9 the top rolls.

10 indicates the roving-rod, and 11 the guides or trumpets.

The device forming the subject of this invention is usually placed at the driving end of the spinning-machine, and is supported on a bracket made adjustable so as to adapt the same for use on spinning-machines in which the height between the rail or platform 5 and the roving-rod differ. The bracket is formed with the base 12, provided with the slot 12', secured by means of a bolt 129 to the rail 5, so that the same can be adjusted transversely. The upright 13 is connected with the base by the curved connection shown in Fig. 1, and supports the whole mechanism. To this upright the post 14, having the slot 15 at its lower part and the stud-pin 16 projecting from its upper part, is secured by the screw 17, the post 14 sliding in suitable ways formed either in the post or in the upright 13, so that when adjusted vertically and secured it forms a rigid support for the heart-shaped cam 18 and the worm-gear 19, formed in one piece with the connecting-sleeve, as is shown in section in Fig. 4. By this vertical adjustment of the post 14, permitted by the slot 15, the worm-gear 19 can be adjusted to engage with the worm by which the same is driven. The grooved arm 20 extends horizontally from the post 14, and to the same the bracket 21, provided with the slot 22, is secured. The bracket 20 is provided with a slot 209, like the slot 100

15, and the bracket 21 is secured to the bracket 20 by a screw 208 in the same manner as the post 14 is secured to the upright 13. By this means the bracket 21 has capacity for adjustment transversely to the rolls and roving-rod independent of the transverse adjustment of the base 12. The fulcrum-pin 23 is adjustably secured to the bracket 21 by a screw passing through the slot 22, and provided with a nut, as is shown in Fig. 4. The bell-crank lever 24 is supported on the fulcrum-pin 23, and the upward-extending arm 25 thereof has its upper end slotted so as to receive a pin or stud projecting from the plate 26, which plate is secured to the roving-rod 10. The arm 27 of the bell-crank lever, extending horizontally, supports the weight 28, and the arm 29 of the bell-crank lever has the contact-arm 30, the free end of which bears on the heart-shaped cam 18, adjustably secured to it. The contact-arm 30 is secured by a screw 309 in a grooved way formed on the outside of the arm 29, and the arm 29 is provided with a slot 307, so that the contact-arm can be adjusted on the arm 29. The worm 31 is secured to the shaft 32, the other end of which shaft is secured to the gear 33, and this gear is driven from one of the drawing-roll gears or from any other gear in the driving-head of the spinning-machine.

The device can be readily adjusted to the varying conditions existing in spinning-machines of different builders. The base 12 can be adjusted transversely to the rolls, the post 35 14, forming the bearing for the cam and worm-gear, has capacity for vertical adjustment, the fulcrum-pin for the lever can be adjusted transversely as well as vertically, and the contact-arm can be adjusted with reference 40 to the operating-cam.

The operation of the device is as follows: Rotary motion being in any convenient manner imparted to the worm 31, the worm-gear 19, and with the same the heart-shaped cam 45 18, receive a slow rotary motion. The bell-crank lever, by reason of the weighted arm 27, is held with the contact-arm bearing on the cam. As the cam is of symmetrical heart shape, the bell-crank lever will be operated 50 by the heart-cam, so that the arm 25, and with the same the roving-rod, will move continu-

ally and uniformly. The roving will therefore be delivered between the drawing and top rolls by the continuously moving and reciprocating guide-eyes or trumpets, and all 55 parts of the drawing and top rolls will thus be subjected to even wear.

Having thus described my invention, I claim as new and desire to secure by Letters Patent—

1. The combination, with the drawing-rolls and the roving-rod of a spinning-machine, of a bell-crank lever having one arm weighted, one arm connected with the roving-rod, and one arm in contact with a cam, the cam 18, 65 the worm-gear 19, the worm 31, shaft 32, and gear, as described.

2. The combination, with the drawing-rolls, the top rolls, and the roving-rod of a spinning-machine, of a bell-crank lever pivoted on the 70 fulcrum-pin 23, adjustably secured to the bracket 21, one arm of the bell-crank lever being connected with the roving-rod, one arm in contact with a cam, and one arm having suspended therefrom the weight 28, the cam 18, 75 and the worm-gear 19, the worm 31, shaft 32, gear 33, and the adjustable support or standard consisting of the transversely-adjustable base 12, the post 14, provided with the slot 15, the screw 17, and arm 20, as described. 80

3. The combination, with the rail 5 and the roving-rod of a spinning-machine, of the standard 13, provided with the slotted base 12, the post 14, provided with the slot 15, the screw 17, the stud-pin 16, the cam 18, and 85 worm-gear 19, the arm 20, provided with ways and a slot, the bracket 21, having slot 22, and adjustably secured to the arm 20, a screw extending through the slot for securing the bracket to the arm, the fulcrum-pin 23, secured in the slot 22, the bell-crank lever consisting of the arm 25, connected with the roving-rod, the arm 27, provided with the weight 28, and the arm 29, the contact-arm 30, secured to the arm 29, the worm 31, the 95 shaft 32, and gear 33, as described.

In witness whereof I have hereunto set my hand.

JOSEPH H. POTTER, JR.
